BRAKE BEAM

Frederic Schaefer, Pittsburgh, Pa.

Application November 13, 1948, Serial No. 59,794

7 Claims. (Cl. 188—223.6)

1

This invention relates to railway car brake beams and, more particularly, to truss type beams which are slidably supported by the side frames of a car truck.

When the brake shoes carried by such beams are forced against the car wheels, the rotation of the wheels tends to move the shoes either upward or downward. This force tends to move the inner sides of the brake heads in that same direction because the heads are supported only at points beyond their outer sides. The result is that in many cases this intermittent canting of the heads causes them to work loose on the ends of the beam. Some heads are provided with tongues that project into the ends of the brake beam's compression member, but heretofore it has been difficult to obtain a tight enough fit to keep the tongues from tilting in the compression member.

It is among the objects of this invention to provide a brake beam of the type discussed above in which a tight fit is assured between brake head tongues and compression member and in which canting of the tongues is prevented independently of the fastening members that secure the tongues and compression member together.

According to this invention the brake beam includes a compression member, on each end of which is mounted a brake shoe supporting member, preferably a brake head, and a tension member having ends secured to the brake heads. The compression member is channel-shape with top and bottom flanges joined by a web. Each brake head is provided at one side with a tongue that projects laterally into the adjoining end of the compression member. The opposite side of the brake head is provided with a laterally projecting lug adapted to be slidably supported by a ledge on a car truck side frame. A plurality of fastening members extend through each tongue and adjoining compression member web at longitudinally spaced intervals to hold them tightly together. Each end portion of the web has an inside rib extending lengthwise of it, and each of the tongues is provided with a longitudinally extending groove that snugly receives the adjoining rib so that there can be no canting or up and down movement of the tongue on the web. The ribs preferably are formed by forging the compression member to offset portions of its web inwardly. It also is preferred that the upper and lower surfaces of the ribs and grooves converge away from the web. In most cases the tongues will be spaced from the top and bottom flanges of the compression member.

The preferred embodiment of the invention is

2

illustrated in the accompanying drawings in which Fig. 1 is a fragmentary plan view of the brake beam supported by a car truck; Fig. 2 is an enlarged horizontal section through one end of the beam; Fig. 3 is an end view of the beam with its upper part shown in section; Fig. 4 is a longitudinal section taken on the line IV—IV of Fig. 2; and Fig. 5 is a cross section taken on the line V—V of Fig. 4.

Referring to the drawings, a truss type brake beam 1 is shown supported by a pair of ledges or short tracks 2 formed on a car truck side frame 3. The brake beam includes a channel-shape compression member 4 and a tension rod 5 spaced apart at the center in the customary manner by a strut 6. Disposed at opposite ends of the compression member are brake shoe supporting members, preferably only brake heads 7, that carry brake shoes 8 which, upon movement of the beam forward, engage the car wheels 9. The brake heads are provided with recesses 12 to receive the ends of the compression member. Each brake head has a generally rectangular body from the front of which the usual shoe-supporting portion 13 extends upward and downward. This portion is reinforced by upright webs 14 integral with it and with the top and bottom of the body. The brake head body is formed from upper and lower spaced parallel walls 16 integrally connected by a front wall 17, an outer wall 18 and an inner back corner portion 19. There is thus formed in the body of the head a slot 21, the entrance to which extends along the inner side of the head. The plane of the slot lies in the plane of the beam which is radial of the wheels. One end of tension rod 5 extends into this slot and is upset and flattened to provide parallel upper and lower surfaces adjacent the inner surfaces of walls 16, and to provide plenty of metal around the opening 22 through the upset end. Aligned with this opening are openings 23 through the upper and lower walls of the slot, as shown in Fig. 3.

In order to be able to locate these head openings in a position that will permit the upset end 45 of the tension rod to be disposed inside of the head body, webs 14 are not parallel to the sides of the head, as in the usual brake head, but, as shown in Fig. 1, extend diagonally across it from the vertical center line of the shoe-supporting portion 50 13 towards the inner rear corner of the head. This allows openings 23 to be positioned much farther inward from the outer side of the brake head body than otherwise would be the case.

The fastening member that extends through 55 aligned openings 22 and 23 includes a sleeve 26

that does not project from the body of the head, and a bolt 27 extending through the sleeve and through washers 28 at its ends. A nut 29 is screwed onto the lower end of the bolt. Due to this arrangement, openings 23 can be large enough for a fastening member of the necessary diameter, and yet can be located close to webs 14, because the relatively small bolt has a head and nut of small enough radius to fit into the spaces between the webs and the centers of the openings. The body of the head can not be made wider in order to provide more room in it for the tension rod and fastening member, because ledges 2 are in the way. The fastening member serves as a pivot around which the rod can turn when the beam is flexed.

This brake beam, instead of being supported by conventional swinging hangers, is supported by ledges 2. For this purpose each brake head has integrally connected to outer wall 18 of its body a lug 31 that projects laterally between the adjacent ledges on the side frame. This lug is flat with parallel upper and lower surfaces and, like slot 21, it lies in the plane of the beam. The lug slides back and forth between the ledges which are inclined so that the inclined beam will slide away from the wheels when the brakes are released.

Projecting laterally from the inner side of the brake head body, near its rear end, is a long flat tongue 32 that extends into the adjoining end of the compression member and engages its web, as shown in Fig. 2. The top and bottom of the tongue are spaced slightly from the upper and lower flanges of the compression member so that there will be no danger of contact at those points preventing the tongue from engaging the web.

It is a feature of this invention that the rear or web-engaging side of the tongue is provided with a central groove 33 that extends horizontally throughout the length of the tongue. The upper and lower walls of this groove preferably diverge toward the web. The adjoining end portion of the web is forged to offset inwardly a long central portion that forms a horizontal rib 34 which fits snugly in the groove in the tongue. The upper and lower surfaces of the rib converge in the same direction and to the same extent as the upper and lower walls of the groove to form a wedge fit. The tongue and rib are provided at longitudinally spaced intervals with aligned openings through which fastening members, preferably rivets 35, extend. The heads at the rear ends of the rivets may be disposed in the recess 36 formed in the compression member by the offset rib. These rivets hold the tongue tightly against the web of the compression member, but they are not subjected to any shearing action because the interengaging rib and groove effectively prevent the tongue from moving transversely of the web or pivoting or canting on it. The connection is improved by making the tongue quite long, so that it can be riveted to the compression member at two or more longitudinally spaced points. Consequently, there is no danger of the tongue working loose in the compression member due to the vertical stresses placed on it when the brakes are applied.

According to the provisions of the patent statutes, I have explained the principle of my invention and have illustrated and described what I now consider to represent its best embodiment. However, I desire to have it understood that, within the scope of the appended claims, the invention may be practiced other-

wise than as specifically illustrated and described.

I claim:

1. A brake beam for use with a railway car truck provided with a pair of beam-supporting ledges, said beam comprising a channel shape compression member having top and bottom flanges joined by a web, a brake shoe supporting member disposed at each end of said compression member, each brake shoe supporting member being provided at one side with a tongue projecting laterally into the adjoining end of the compression member and at the other side with a laterally projecting lug adapted to be slidably supported by the adjoining ledge, and a plurality of fastening members extending through each tongue and adjoining compression member web at longitudinally spaced intervals to hold them tightly together, each end portion of said web having an inside rib extending lengthwise of it, and each of said tongues being provided with a longitudinally extending groove snugly receiving the adjoining rib.

2. A brake beam for use with a railway car truck provided with a pair of beam-supporting ledges, said beam comprising a channel shape compression member having top and bottom flanges joined by a web, a brake head disposed at each end of said member, each head being provided at one side with a tongue projecting laterally into the adjoining end of the compression member and at the other side with a laterally projecting lug adapted to be slidably supported by the adjoining ledge, each end portion of said web having an inside horizontal rib, each of said tongues being provided with a horizontal groove snugly receiving the adjoining rib, and a plurality of rivets connecting each adjoining rib and tongue at longitudinally spaced intervals.

3. A brake beam for use with a railway car truck provided with a pair of beam-supporting ledges, said beam comprising a channel shape compression member having top and bottom flanges joined by a web, a brake shoe supporting member disposed at each end of said compression member, each brake shoe supporting member being provided at one side with a tongue projecting laterally into the adjoining end of the compression member and at the other side with a laterally projecting lug adapted to be slidably supported by the adjoining ledge, and a plurality of fastening members extending through each tongue and adjoining compression member web at longitudinally spaced intervals to hold them tightly together, each end portion of said web having an inwardly offset central portion extending lengthwise thereof to form a horizontal rib, and each of said tongues being provided with a longitudinally extending groove snugly receiving the adjoining rib.

4. A brake beam for use with a railway car truck provided with a pair of beam-supporting ledges, said beam comprising a channel shape compression member having top and bottom flanges joined by a web, a brake shoe supporting member disposed at each end of said compression member, each brake shoe supporting member being provided at one side with a tongue projecting laterally into the adjoining end of the compression member and at the other side with a laterally projecting lug adapted to be slidably supported by the adjoining ledge, and a plurality of fastening members extending through each tongue and adjoining compression member web at longitudinally spaced intervals to hold them

tightly together, each end portion of said web having a rib extending lengthwise of it, and each of said tongues being provided with a longitudinally extending groove snugly receiving the adjoining rib, the upper and lower surfaces of said ribs and grooves converging away from said web.

5. A brake beam for use with a railway car truck provided with a pair of beam-supporting ledges, said beam comprising a channel shape compression member having top and bottom flanges joined by a web, a brake shoe supporting member disposed at each end of said compression member, each brake shoe supporting member being provided at one side with a tongue projecting laterally into the adjoining end of the compression member and at the other side with a laterally projecting lug adapted to be slidably supported by the adjoining ledge, the tongues being spaced from said top and bottom flanges, and a plurality of fastening members extending through each tongue and adjoining compression member web at longitudinally spaced intervals to hold them tightly together, each end portion of said web having an inside rib extending lengthwise of it, and each of said tongues being provided with a longitudinally extending groove snugly receiving the adjoining rib.

6. A brake beam for use with a railway car truck provided with a pair of beam-supporting ledges, said beam comprising a channel shape compression member having top and bottom flanges joined by a web, a brake head disposed at each end of said member, each head being provided at one side with a tongue projecting laterally into the adjoining end of the compression member and at the other side with a laterally projecting lug adapted to be slidably supported by the adjoining ledge, the tongues being spaced from said top and bottom flanges, each end portion of said web having an inwardly offset central portion extending lengthwise thereof to form a horizontal rib with inwardly converging upper and lower surfaces, each of said tongues being provided with a longitudinally extending groove

snugly receiving the adjoining rib, and a plurality of rivets connecting each adjoining rib and tongue at longitudinally spaced intervals.

7. A brake beam for use with a railway car truck provided with a pair of beam-supporting ledges, said beam comprising a channel shape compression member having top and bottom flanges joined by a web, a brake head disposed at each end of said member, each head being provided at one side with a recess receiving the adjoining end of the compression member and with a long tongue projecting into the compression member, the opposite side of the head having a laterally projecting lug adapted to be supported by the adjoining ledge, a plurality of fastening members extending through each tongue and adjoining compression member web at longitudinally spaced intervals to hold them tightly together, each end portion of said web having an inside rib extending lengthwise of it and each of said tongues being provided with a longitudinally extending groove snugly receiving the adjoining rib, each head having a slot extending into it from its tongue side and disposed in the plane of the beam, a tension rod having its ends projecting into the slots in the heads, each end of the rod and the slot walls above and below it being provided with aligned openings, and fastening members in said openings pivotally connecting the tension rod and brake heads together.
